TUNING MECHANISM FOR RADIO APPARATUS

Vernon C. Macnabb, Indianapolis, Ind., assignor to Fairbanks, Morse & Co., Chicago, Ill., a corporation of Illinois

Application March 8, 1937, Serial No. 129,639

12 Claims. (Cl. 116—124.1)

This invention relates to tuning mechanism for radio apparatus, and more particularly to an improved tuning dial organization for radios of multiple wave-band type.

5 It has been the general practice heretofore, to provide in connection with multiple wave-band radio apparatus, a single tuning dial having thereon tuning indicia for the several bands. One of the disadvantages of such a dial arrangement 10 is that all of the tuning indicia are simultaneously visible, resulting in many instances, in a confusion of wave band indication during tuning. Moreover, where all the indicia for a plurality of wave bands are simultaneously visible, the arrangement 15 of indicia offers of itself a degree of confusion to the operator. Accordingly, it is an object of the present invention to provide a radio tuning indicator characterized by the selective display of the tuning indicia for but one wave band at a time.

Among other objects of the invention are the provision of a tuning indicator for a multi-wave band radio having visible only the band indicia of the particular wave band desired; the provision 25 of a tuning indicator having a separate dial member for each wave band, with the dial members relatively displaceable so that only one thereof will be visible at any one time, and the provision of regulating means for the indicator, adapted 30 to operate the several dial members in sequence to obtain the visibility of but one dial member at a time, the regulating means being operated preferably by the control element provided for changing the circuit arrangement of the radio 35 from one wave-band to another.

Further objects and advantages will appear from the description and accompanying drawings, in which:

Fig. 1 is a front elevation of a partly assembled 40 radio chassis, illustrating the improved wave-band indicator of this invention; Fig. 2 is a fragmentary plan view of the radio chassis of Fig. 1, showing the front panel of the radio in section, and the disposition of the indicator mechanism 45 relative thereto; Fig. 3 is an enlarged, fragmentary sectional elevation of the radio chassis and front panel, illustrating certain details of the improved indicator, the view being taken from line 3—3 in Fig. 1; Fig. 4 is an enlarged side elevation 50 of a part of the indicator, with portions thereof shown in section, as taken along line 4—4 in Fig. 1; Fig. 5 is a front elevation of the device shown by Fig. 5, as viewed from line 5—5 thereon, the view, however, showing certain of the elements in an altered position from that indicated 55

for these parts in Fig. 4; Fig. 6 is a view in detail, of a portion of the mechanism shown by Fig. 4; Fig. 7 is a sectional view of a part of the mechanism, as taken along line 7—7 in Fig. 4, and Fig. 8 is an elevation shown partly in section, of the mechanism of Fig. 4, as viewed from line 8—8 thereon.

Referring now to the drawings by suitable numerals of reference, the improved indicator is operatively associated with the tuning mechanism of a multi-wave band radio, as will now appear. As shown in Figs. 1, 2, and 3, the radio chassis is indicated generally at 10, the chassis supporting the radio instruments and apparatus, as for example, a multiple capacity unit of variable type indicated at 11, and a multiple circuit switching device 12 provided for adjusting the apparatus to receive signals in any one of a number of different wave bands. The switching device 12 is operated by a shaft 13 extending to the front of the radio panel 14, the shaft being provided with a control handle or knob 15 for manual manipulation thereof. For convenience and simplicity of control, the shaft 13 controlling the shifting of the circuit connections to accommodate the different wave bands, is utilized to regulate the wave band indicator mechanism now to be described.

The panel 14 is provided with an opening 16 of square, circular or other desired configuration, the opening being closed preferably on the back or inner face of the panel, by a transparent member 17 such as a glass plate. By preference, the glass 17 is carried by a substantially rigid opaque member or mask 18 formed of either metallic or non-metallic sheet material, the mask 18 being supported by the chassis 10 in any suitable manner, as by the bolts 19 and spacer sleeves 20 extending between the member and a bracket 21 secured to a side wall 22 of the chassis. Mounting of the glass 17 on the mask 18 may be effected in any desired manner, as by the clips 23 shown in Fig. 1. As appears in Figs. 2 and 3, the sleeves 20 serve to space the member 18 and glass 17 outwardly of the chassis wall 22 so that in the assembly relation of the chassis 10 and panel 14, the glass will seat against the inner side of the panel in a position to close the panel opening 16.

Referring to Figs. 1 and 3, the mask 18 is provided with a substantially semi-circular opening 50 or window 24 to permit observation of tuning indicia disposed on relatively displaceable dial elements arranged rearwardly of the member 18, as will later appear. In addition, a second slot or window 25 of smaller extent is formed in the

member 18, above the slot 24 in the position shown in Fig. 1, this second slot being provided to permit observation of wave band indicia associated with the tuning indicia, as will be presently described. Arranged rearwardly of and in relatively close adjacency to the member 18, are a plurality of substantially semi-circular dial elements, four being shown in the present example, and numbered 26, 27, 28, and 29, the element 26 being that closest to the member 18. The elements are formed of relatively thin, sheet material, such as steel, aluminum or bakelite, and each is provided with a portion 39 extended upwardly from the mid-section of the semi-circular portion of the element, for a purpose presently to appear. As shown in Figs. 2 and 3, the elements are arranged in horizontally spaced relation, one in back of another, so that in the position shown, only the element 26 will have surface portions thereof in register with and exposed through the slots 24 and 25, respectively. Arranged along that surface of the dial element 26 which is exposed through the slot 24, are tuning graduations 31 and wave length indicia 32. The surface of the extension 39 on element 26 which is exposed through the slot 25, is provided with a suitable indicator of the wave band corresponding to the graduations 31 and wave length indicia 32, this indicator in the present example, being the word "Broadcast". Each of the remaining elements 27, 28, and 29 is similarly provided with an indicator of a particular wave band and indicia of wave length corresponding thereto, although such indicia and band indicators are not shown in the present disclosure. It is understood, of course, that the dial elements are associated with a variable tuning device of the radio to indicate the tuning condition thereof. In the present example, the tuning device is the variable capacity device or condenser 11. The rotary elements of the condenser are operated through the condenser shaft 34, and in the present example the shaft extends toward the radio panel 14, and has a dial hand or pointer 36 mounted thereon which plays over the dial face bearing the tuning indicia visible through window 24, as the condenser is operated.

As before noted, with the elements 26 through 29 in the positions shown in Figs. 2 and 3, only the tuning indicia and wave band indicator on element 26 are visible through the slots 24 and 25. To expose the indicia and wave band indicator on element 27, the element 26 is adapted in a manner later appearing, to be displaced sufficiently to permit visibility of the tuning indicator element 27 through the slots 24 and 25. Likewise, the element 27 is displaceable so as to expose the tuning indicia and band indicator on element 28, and similarly the element 28 is displaceable to expose the indicia on element 29. Since in the present example, the element 29 is the last of the group, it may be retained in its original position and thus will be exposed only when all the other elements have been displaced. Hence, it will be readily observed from the foregoing, that at any given time, only one of the elements 26 through 29 will be in position for exposure of its band indicator and tuning indicia through the windows 24 and 25.

The dial elements 26, 27, and 28 are adapted for sequential displacement, for the purpose above noted, through mechanism now to be described. Each of these elements is formed with a lateral extension 37 terminating in a projection or tail piece 38. The elements are pivotally supported

upon a sleeve 39 mounted on a shaft or plunger 41, the sleeve extending through the extensions 37, as shown in Fig. 4. As a means for preventing frictional or rubbing contact between adjacent dial elements, and also for providing greater rigidity of the elements at the zone of pivotal support, each of the elements is secured in any suitable manner, to a spacer member 42. The dial extensions and spacers are confined longitudinally of the sleeve, between a shoulder 44 formed on one end of the sleeve and a removable end plate 45 at the opposite end of the sleeve, the plate 45 being retained in assembly by a screw 46 threadedly engaging the shaft 41. To prevent longitudinal displacement of the sleeve 39 on shaft 41, the shaft end 40 is formed of reduced diameter, to provide a shoulder 47 against which the shouldered sleeve end 44 seats, in the assembly of the parts.

The shaft or plunger 41 is journalled for longitudinal sliding movement, in a bearing member 48 carried by and extending through a portion of the bracket 21 heretofore noted, said bearing member having an external, rounded shoulder 50 for a purpose later to appear. The shouldered portion of the bearing member is disposed outwardly of one side of the bracket 21 and adjacent the shouldered end of the dial supporting sleeve 39, as shown in Fig. 4. Formed by preference, as an integral part of the bearing 48 and extending through bracket 21, is a tubular member or cylinder 51. The shaft 41 extends into the cylinder 51 and is provided with a head element 54, the peripheral surface of which seats against the internal wall surface of the cylinder, after the manner of a piston. A compression spring 55 is sleeved about the shaft 41, and confined between the shaft head 54 and an internally shouldered part of the cylinder, thus serving to bias the sleeve 39 and dial elements thereon in a direction away from the panel 14.

Mechanism of a preferred type now to be described, is provided for controlling both longitudinal shifting of the shaft 41 and hence of the dial elements 26 through 29, and pivotal displacement of the dial elements for the purpose heretofore noted. The purpose for the longitudinal shifting of the dial elements will appear as the description proceeds.

As shown in detail in Figs. 4 through 8, the dial shifting mechanism comprises a substantially channel-shaped frame 57 provided with a slot 58 in the bridge portion 59 thereof, the slot extending substantially the length, yet terminating short of the ends of said bridge portion. The sides 61 of the frame 57 are substantially triangular in side elevation, as shown in Fig. 4, the edge 62 of each side corresponding to the hypotenuse of the triangle, serving as a camming edge for a purpose presently to appear. In the assembly of the frame to the dial mechanism, the shaft 41 extends through the slot 58, while the solid portions of the bridge engage the shoulder 44 of the dial carrying sleeve 39. The frame sides 61 straddle the shaft and the camming edges 62 engage the rounded bearing shoulder 50, in the manner shown in Fig. 4. From the foregoing, it will be observed that the spring 55 acting on the shaft 41, and hence on the sleeve 39 serves through these elements to urge the camming edges 62 of the frame against the shoulder 50.

As a means for attaining stability of the frame 57 in assembly and during its operation as will be later described, and also, for confining the frame to a linear movement of an extent deter-

mined by the length of the frame slot 58, there is provided a shaft or plunger 64 spaced from the shaft 41 and longitudinally slidably journaled in a bearing member 65 secured to the bracket 21, with the shaft extending through the frame slot 58. The shaft 64 is urged in one direction of its slidable movement by a spring 67 sleeved upon the shaft and bearing against the shaft head 68. The spring, shaft, and shaft head are arranged 10 within a cylinder 70 which may be formed as an integral part of the bearing member 65. Threadedly engaging an internal bore in the outer end of shaft 64, is a rod 71 provided for a purpose later to appear, the rod having a flange 72 seating against the end of shaft 64 and in engagement with the bridge portion 59 of the sliding frame 57. The bearing member 65 extends outwardly from bracket 21 a greater distance than does the bearing member 48 heretofore described 15 20 in connection with shaft 41, and has its exposed end 73 rounded as shown, to provide a bearing seat for the camming edges 62 of frame 57. Thus the frame is confined between the end 73 of bearing member 65 and the flange 72 on rod 71, so 25 that the spring 67 acting on the shaft 64 and hence on the flange 72, tends to urge the camming edges 62 of the frame against the bearing seat 73.

It will be observed from the foregoing description and from an inspection of Fig. 4, that downward displacement of the frame 57 from its upper extreme position shown in Fig. 4, will result in an outward shifting of the plungers or shafts 41 and 64, against the pressure of the respective springs 55 and 67 acting thereon, this shifting of the 30 shafts being effected by reason of the wedging action of the frame 57 on the said shafts. The provision for the shifting of the shafts, particularly shaft 41, is made for the purpose of displacing the assembly of dial elements so that the 35 particular element being disclosed will be close to the window 24 in panel 14. By regulating the actuation of frame 57 to attain a step-by-step movement thereof, the shifting of the dial elements may be controlled so that say upon the 40 placement of dial element 26, the dial element 27 will be shifted into substantially the spacial position formerly occupied by element 26. Further downward movement of the frame 57 during displacement of the element 27, will bring the element 28 into the space formerly occupied by element 27, and so for the last element 29. Thus 45 successive movements of the frame in steps, will attain the desired shifting of the elements, and it is to be noted that the results above described 50 will occur in reverse order upon successive upward movements of the frame 57.

Actuation of the frame in a step-by-step manner, is attained through the operation of the circuit changing switch 12 through the control shaft 60 13. For this purpose, the lower end of the frame 57 is provided with a laterally extending arm 74 having therein a slot 75, the longitudinal axis of which is substantially at a right angle to that of the frame slot 58. Extending through the slot 75 65 is an element or rod 76 having one end thereof secured in any suitable manner, to an actuating arm 79. The arm 79 is operatively secured to the switch control shaft 13 by a lock screw 82. Thus by rotating the shaft 13, through the handle 15, the frame 57 will be actuated through the arm 79 and rod 76 in the slot 75 of the frame arm 74. As will be readily understood, the purpose for 70 the slot 75 is to permit movement of the actuating rod 76 therealong during rotation of the arm 79, since the frame 57 is confined to linear move-

ment only. In operating switch 12 to change the radio circuit connections, the switch shaft 13 is rotated in steps, the angular extent of rotation thereof in each step being determined by the spacing of the switch contacts (not shown). Accordingly, the stepped movement of shaft 13 will effect a corresponding stepped movement of the frame 57, and the extent of linear movement of the frame in each step is correlated with the extent of rotary movement of shaft 13 in each step 10 so as to attain the desired degree of shifting movement of the dial elements. Such correlation of movements is effected through proper design and relation of the elements above described, operatively connecting the shaft 13 and frame 57. 15

Turning now to the mechanism for effecting successive displacements of the several dial elements, this is effected simultaneously with the shifting of the dial elements by the frame 57, through a member 86 secured to one arm of the 20 frame, as by the screws 87. The member 86 which may be a substantially rectangular plate formed of any suitable rigid material, extends outwardly and longitudinally of the frame, being parallel to the arms of the frame, and is provided with a central aperture or opening 88 of triangular aspect. The marginal portion of the plate aperture, defining a side corresponding to the hypotenuse of the triangularly shaped opening 88, is stepped at 90, 91, 92, and 93, as shown 30 in Fig. 6, with the lower ends of the stepped portions provided with an outturned lip or finger 94, 95, 96, and 97 respectively, as shown in Fig. 5. The lips or fingers on plate 86 are provided for effecting a pivotal displacement of the dial elements, in a manner presently to be described.

Each of the dial elements is urged to its initial position behind the member 18 and in register with the windows 24 and 25 therein, by a spring 98 having one end secured to the dial extension 40 37 and its opposite end secured to the rod 71 on shaft 64. Four such springs are shown, one for each of the dial elements 26 through 29, although the spring for the last dial element 29 may be omitted, if desired, as this element is normally 45 retained in its original position at all times. The position of the dial elements behind the member 18 so that the tuning indicia thereon will be in register with the windows 24 and 25, is determined by a suitable stop element 102 (Figs. 3 50 and 5) carried by the bracket 21. If desired, the stop may be provided by one of the supporting elements for the mask 18, such element being comprised of a bolt 19 and sleeve 20 as heretofore noted. The stop is provided with an abutment 103 sleeved thereon, the abutment being formed of any suitable material, such as aluminum or bakelite. Moreover, securing the springs 98 to the rod 71 on shaft 64 serves to maintain the axis of each spring in the plane of its dial 60 element during shifting of the dial elements by the frame 57, as shaft 41 supporting the dial elements, and shaft 64 supporting rod 71 are moved an equal distance upon each actuation of the frame 57.

The arrangement of the plate 86 on frame 57 is such that with the plate and frame in the uppermost position, as shown in Fig. 4, the dial elements will be disposed in their initial position (Figs. 2 and 4) with the tail pieces 38 thereof 70 extending through the lower end of the opening 88 in plate 86 (Figs. 4 and 6). In this position of the several dial elements, the tail piece 38 of dial element 26 is disposed to underlie the actuating finger 94. The tail pieces 38 of the other 75

dial elements 27, 28, and 29 are in vertical register but out of engagement with the fingers 95, 96, and 97, respectively. Thus upon downward movement of the frame 57 and plate 86, as effected by actuation of shaft 13, the finger 94 will act upon the tail piece 38 of dial element 26, to pivot the dial element upwardly and outwardly from its initial position behind the windows 24 and 25, into the position indicated at 10 105 in Fig. 5. In the displaced position 105 of the element 26, the edge 106 of its extension 37 rests against the plate 86, and the element is retained in such position against the bias of its spring 98, by the finger 94 and surface portion of 15 the plate 86. Simultaneously with the displacement of dial element 26 and as a result of the downward movement of the frame 57 as heretofore described, all the dial elements are shifted toward the panel 14 so as to bring the next succeeding dial element 27 into the space formerly 20 occupied by dial 26, in register with the windows 24 and 25. Successive downward movements of the frame 57 and plate 86 effect in turn, similar 25 positioning of the other dial elements 27 and 28. Actuation of shaft 13 so as to move frame 57 and plate 86 upwardly, successively releases the 30 dial elements, in the reverse order of their displacement, permitting the springs 98 to return the elements to their original positions. At the same time, the dial elements are shifted axially 35 of shaft 41 and in a direction away from the panel 14, under the action of the camming frame 57 and springs 55 and 57 acting respectively, on shafts 41 and 64, so as to return the dials to their original position rearwardly of the panel.

From the foregoing, it will be observed that the mechanism for positioning the tuning dial elements is actuated and controlled by the circuit changing device for the radio, and the arrangement is such that upon actuation of the circuit changing device to effect circuit connections for reception on a particular wave band, the tuning dial element corresponding to such wave band will be disposed in register with the windows 24 and 25 for visibility of the tuning indicia on such dial. Thus, when the circuit changing device is in position to effect reception on the "Broadcast" band, this being one extreme position of the device, the dial 26 which is the "Broadcast" band dial, will be in position for observance of its tuning indicia through window 24 and band indicator "Broadcast" through window 25. When the switch 12 is actuated by shaft 13, through one step to the next succeeding position determining a different circuit connection for reception on another wave band, dial 27 corresponding to such wave band, will be in position for observance of its tuning indicia through window 24 and its band indicator through window 25, and similarly for the remaining dial elements.

Thus, the present invention provides a tuning indicator mechanism for a multi-wave-band radio, the indicator being characterized by the selective display of tuning indicia for but one wave band at a time. Moreover, the display of tuning indicia corresponding to a given wave band is made coincidentally with the actuation of the circuit changing device of the radio, to effect the circuit connections for reception on the given wave band.

It is to be understood that the invention is not to be limited to the herein described embodiment thereof, but that alterations and modifications may be made therein without departing

from the spirit and full scope of the invention, as defined by the appended claims.

I claim:

1. A tuning dial mechanism of the character described, comprising a plurality of dial elements normally disposed in spaced relation, a member pivotally supporting said dial elements, said member being capable of axial movement to effect axial displacement of said elements, and means operatively associated with said dial elements and with the supporting member therefor, adapted for effecting concurrently, pivotal and axial displacement of said dial elements. 5 10

2. A tuning dial mechanism of the character described, comprising a plurality of dial plates normally disposed in spaced, parallel relation, a member pivotally supporting said plates, said member being capable of axial shifting movement to effect axial displacement of said dial plates, means operable to axially shift said supporting member and dial elements, and means operated by said shifting means, adapted for pivotally displacing said dial plates. 15 20

3. A tuning dial mechanism of the character described, comprising dial elements normally disposed in spaced relation, means supporting said elements for both pivotal and axial displacement, and means operatively associated with said dial elements, adapted for effecting pivotal and axial displacement of each of said dial elements. 25 30

4. A tuning dial mechanism of the character described, comprising dial elements normally disposed in spaced, parallel relation, means supporting said elements for both pivotal and axial displacement, and means operatively associated 35 with said dial elements and said supporting means, adapted for effecting, coincidentally, pivotal and axial displacement of each of said dial elements. 35

5. In combination with radio apparatus including a tuning device, a panel and an opening in said panel, a tuning dial mechanism comprising dial plates arranged in spaced, parallel relation, means supporting said plates for both pivotal and axial displacement, means biasing said plates to a position in register with said panel opening, and means operatively associated with said dial plates, adapted for effecting a coincidental pivotal and axial displacement of each of said dial plates out of register with said panel 40 45 50

6. In combination with radio apparatus including a tuning device, a circuit changing device, a panel and an opening in said panel, a tuning dial mechanism comprising dial elements arranged in spaced, parallel relation, means supporting said elements for both pivotal and axial displacement, means biasing said elements to a position in register with said panel opening, and means operatively associated with said dial elements and actuated by said circuit changing device, for effecting sequential displacement of said dial elements out of register with said panel opening and coincidentally therewith, axial displacement of said elements. 60 65 70

7. In combination with radio apparatus including a tuning device and a circuit control device, a tuning dial mechanism comprising dial plates arranged in spaced, parallel relation, means supporting said elements for both pivotal and axial displacement, a camming member operatively associated with said supporting means, adapted for effecting axial displacement of said dial plates, actuating mechanism for said camming means, operated from said circuit control 70 75 80

device, and means on said camming member, adapted coincidentally with the actuation of said camming member, to effect pivotal displacement of said dial plates.

5. 8. In combination with radio apparatus including a tuning device, a circuit control device, a panel and an opening in said panel, a tuning dial mechanism comprising dial elements arranged in spaced, parallel relation, means supporting said elements for both pivotal and axial displacement, means for biasing said dial elements to a position in register with said panel opening, a camming member operatively associated with said supporting means, adapted for 10 effecting axial displacement of said dial elements, actuating mechanism for said camming means, operated from said circuit control device, and means on said camming member, adapted coincidentally with the actuation of said camming member, to effect pivotal displacement of said dial elements out of register with said panel opening.

9. In combination with radio apparatus including a tuning device, a tuning dial mechanism 25 thereof, comprising dial elements arranged in spaced relation, means supporting said elements for both pivotal and axial displacement, a cam operatively associated with said dial elements for axial displacement thereof, and a member movable with said cam and provided with spaced projections arranged for engagement with said dial elements as the cam is operated, to effect pivotal displacement of said dial elements.

10. In combination with radio apparatus including a tuning device and a circuit control device, a tuning dial mechanism comprising dial elements arranged in spaced relation, means supporting said elements for both pivotal and axial displacement, a cam operatively associated with

said dial elements for axial displacement thereof, said cam being actuated by said circuit control device, and a member movable with said cam and provided with spaced projections thereon arranged for engagement with said dial elements as 5 the cam is operated, to effect pivotal displacement of said dial elements.

11. In combination with radio apparatus including a tuning device, a tuning dial mechanism therefor, comprising dial elements arranged in 10 spaced relation, a projection on each of said elements, means supporting said elements for both pivotal and axial displacement, a cam operatively associated with said dial elements for axial displacement thereof, and a member movable 15 with said cam and provided with spaced projections arranged for successive engagement with the projections on said dial elements as the cam is operated, to effect a successive pivotal displacement of said dial elements. 20

12. In combination with radio apparatus including a switch for adjusting the apparatus to receive signals in any of a plurality of wave bands, a control for said switch, a plurality of dial plates, each bearing tuning indicia for signals in one of said wave bands, a panel for concealing said plates, having an opening for revealing the tuning indicia of any one thereof at a particular time, a shaft, means mounting said dial plates for independent pivotal movement and 25 conjoint translatory movement on said shaft, toward and from said panel opening, means for moving the dial plates as aforesaid, means operatively interconnecting said switch control and said dial moving means, and a manipulating element for effecting joint actuation of said switch control and dial moving means. 30 35

VERNON C. MACNABB.
